UNITED STATES PATENT OFFICE.

JOHN HEGERHORST, OF HAMMOND, INDIANA, ASSIGNOR OF ONE-HALF TO JOHN S. BRICKNELL, OF HAMMOND, INDIANA.

SATCHEL-HANDLE.

1,317,923.

Specification of Letters Patent.

Patented Oct. 7, 1919.

Application filed October 25, 1918. Serial No. 259,626.

To all whom it may concern:

Be it known that I, JOHN HEGERHORST, a citizen of the United States, residing at Hammond, in the county of Lake and State 5 of Indiana, have invented new and useful Improvements in Satchel-Handles, of which the following is a specification.

This invention relates to handles for grips, traveling bags, valises, satchels and the like, 10 and its object is to provide a handle which is detachable from the case for the purpose of discouraging theft thereof, the handle being removed when the owner wishes to leave the case, so that the latter now cannot 15 be conveniently carried.

The invention also has for its object to provide a handle fastening which precludes the possibility of the attachment of a handle to the case other than the proper one.

20 A further object of the invention is to associate with the handle fastening a novel means for locking the case in closed position.

With the objects stated in view the invention consists in a combination and arrangement of parts to be hereinafter described and claimed, and in order that the same may be better understood, reference is had to the accompanying drawing forming a part of 25 this specification.

In the drawing,

Figure 1 is an elevation of the device, partly broken away;

Fig. 2 is a longitudinal section of the lock;

35 Figs. 3 and 4 are sections on the lines 3—3 and 4—4 of Fig. 2, respectively; and

Fig. 5 is a perspective view of a detail.

Referring specifically to the drawing, 10 denotes a fragment of the grip, satchel or

40 other case, the same being provided with a handle 11 for carrying the same, and said handle being detachably connected to the case, so that when the owner wishes to leave the same temporarily, he can remove the 45 handle. The case cannot now be conveniently carried, and the person carrying the same is also apt to excite suspicion, so that danger of theft of the case is reduced to a minimum.

50 The detachable fastening for the handle 11 comprises the following parts:

The top of the case has the usual opening which is lined on opposite sides by two parallel longitudinal metal strips 12 and 13, 55 respectively, having inturned flanges 12^a and

13^a, respectively, which overlap when the case is closed, with the flange 12^a on the outside or above the flange 13^a.

To the outer face of the flange 12^a are riveted or otherwise secured two housings 60 14 and 15, respectively, which are spaced to correspond to the spacing of the ends of the handle 11, and between these two housings, the flange 12^a is provided with another and intermediate housing 16. The housings 14 65 and 15 have lateral base flanges 17 which seat beneath the flange 12^a and are secured thereto by suitable fasteners 17^a.

One end of the handle 11 is fitted with a headed stud 18 which seats loosely and removably in an aperture 18^a in the outer end wall of the housing 14, so that the handle 70 can be swung upwardly and downwardly to bring its other end away from and toward the housing 15. The last-mentioned end of 75 the handle is detachably connected to the housing 15 in which latter it is locked by a means which will now be described.

The housing 16 contains a slidable latch bolt 18^b having at one end a hook 18^c the 80 bill 18^d of which points upwardly. The hook extends from the bottom of the bolt and from the top thereof, at the same end as the hook, extends a finger piece 18^e the shank of which projects through a slot 18^f in the housing 16. The flange 12^a has a slot 19 and the flange 13^a a recess 19^a to accommodate the shank of the hook 18^c. The other end of the bolt passes into the housing 15 and here carries a plate 20 having on its outer 85 face a series of outstanding studs 20^a. At the top of the plate is a rearward flange 21 to which the bolt 18^b is loosely connected, as shown at 21^a so that it may be rocked or tilted for a purpose to be presently described. 90 As the plate 20 is carried by the bolt 18^b, and the latter is movable in the direction of its length, the studs 20^a can be advanced and retracted. A spring 22 engages the hooked end 95 of the bolt for advancing the same.

In the top of the housing 15 is an aperture 24 through which is adapted to be inserted a keeper tongue 25 on the end of the handle 11. This tongue has apertures 25^a corresponding in size and location to the size and 100 grouping of the studs 20^a, so that the latter may enter the same when the tongue is passed through the aperture 24 into the housing 15. It will be noted that three studs are provided, the middle one being larger than 105 110

the others, so that the chances of reaching the bottom of the lock with a tool for the purpose of tampering with the same, are greatly reduced. With the middle stud in 5 one position, various combinations can be produced by moving the other studs up or down on the plate 20, and the combination can also be changed by changing the position of the middle stud. Numerous combinations 10 of apertures 25^a in the tongue 25 are therefore rendered possible.

The flange 12^a has two transverse rows 27 and 28, respectively, of apertures, the former being designed to receive outstanding lugs 29 on the bottom edge of the tongue 25 when the latter is inserted into the housing 15 and locked by the studs 20^a. To the under side of the flange is riveted or otherwise fastened, as shown at 30, a spring 15 metal plate 31 provided with three projecting tongues 31^a having upstanding studs 31^b which are positioned to seat in the apertures 28 and to project therefrom a sufficient distance into the housing 15 to serve 20 as stops for the plate 20, the sides of the studs which are thus engaged being flattened. When the tongue 25 is inserted into the housing 15, the lugs 29 pass through the apertures 27 and depress the plate 31 25 to retract the studs 31^b for release of the plate 20, which is now advanced by the spring 22 to seat the studs 20^a in the apertures 25^a. The flange 12^a forms a solid rest 30 for the inner end of the tongue 25 from which the lugs 29 project, which latter only pass through the apertures 27, and the flange therefore limits the downward movement 35 of the tongue 25 into the housing 15, so that the apertures 25^a will be accurately positioned in line with the studs 20^a.

The tongue 25 is pivoted, as shown at 23, to a shank 23^a extending from the end of the handle 11, which enables the handle to be folded on the case 10 to conform with 45 baggage room requirements that other articles may be placed on the case.

The bolt 18^b also locks the case 10 closed, this being done by the hook 18^c. The strip 12 carries, inside the case 10, a pair of outstanding tongues 32 having alined slots 32^a, and the strip 13 carries a slotted tongue 33 adapted to seat between the tongues 32 when the case is closed, the slot 33^a of the tongue 33 then registering with the slots 32^a. 50 The hooked end of the bolt 18^b is so positioned that the upstanding hook bill 18^a can be passed through the registering slots 32^a and 33^a, whereupon the case is locked closed. To unlock the case, the bolt 18^b 55 must be tilted or pushed inward to withdraw the hook bill from the slots. The bolt is held normally pushed upward by a bottom leaf spring 34 formed integral with the part 31. The length of the slots 32^a and 33^a is 60 such that the bolt 18^b can be moved length-

wise a sufficient distance to lock or unlock the handle 11.

To remove the handle 11, it is necessary only to move the bolt 18^b rearwardly by taking hold of the finger piece 18^e, which withdraws the studs 20^a from the apertures 25^a. The tongue 25 is now free and may be withdrawn from the housing 15, after which the other end of the handle may be disconnected from the housing 14. The hook bill 75 18^a remains in the slots 32^a and 33^a during this operation, and hence the case 10 remains locked closed. When the bolt 18^b is shifted rearward to unlock the handle, the studs 31^b come in front of the plate 20 and thus prevent the bolt from being moved forward, and as the finger piece 18^e is outside and overhanging the slot 18^f, the bolt cannot be depressed to take the hook bill 18^a 80 out of the slots 32^a and 33^a to unlock the 85 case. To unlock the case, the tongue 25 must be inserted into the housing 15 to withdraw the studs 31^b from the plate 20, whereupon the bolt 18^b is left free to be slid to the left a sufficient distance to bring the 90 finger piece 18^e in line with the slot 18^f. The bolt can now be depressed to take the hook bill 18^a out of the apertures 32^a and 33^a, which unlocks the case. It will therefore be seen that the tongue 25 also has the function of a key for unlocking the case. 95

I claim:

1. The combination with a valise or the like, and a removable handle therefor; of a 100 slideable and tilttable latch bolt carried by the valise, means in the valise engageable by the bolt for locking the valise, the bolt being disengageable by a tilting movement, a latch keeper tongue on the handle, means on the bolt and engageable with said tongue 105 for locking the handle to the valise, and means releasable by the tongue for preventing a sliding movement of the bolt to a position where it may be tilted.

2. The combination with a valise or the 110 like, and a removable handle therefor; of a slideable and tilttable latch bolt carried by the valise, a latch keeper tongue on the handle, means on the bolt and engageable with said tongue for locking the handle to the valise, 115 said means being operable by a sliding movement of the bolt, means in the valise and engageable by the bolt for locking the valise, said means being operable by sliding and tilting movements of the bolt in the order 120 named, and means for preventing such sliding movement of the bolt.

3. The combination with a valise or the like, and a removable handle therefor, of a slideable and tilttable latch bolt carried by the 125 valise, a latch keeper tongue on the handle, means on the bolt and engageable with said tongue for locking the handle to the valise, said means being operable by a sliding movement of the bolt, means in the valise and en- 130

gageable by the bolt for locking the valise, said means being operable by sliding and tilting movements of the bolt in the order named, and means for preventing such sliding movement of the bolt, said means being controlled by the aforesaid tongue.

4. The combination with a valise or the like, and a removable handle therefor; of a 10 slideable and tilttable latch bolt carried by the valise, means in the valise engageable by the bolt for locking the valise, the bolt being disengageable by a tilting movement, a latch keeper tongue pivotally connected to the handle, means on the bolt and engageable with said tongue for locking the handle to the valise, and means releasable by the tongue for preventing a sliding movement of the bolt to a position where it may be tilted.
5. The combination with a valise or the 20 like, and a removable handle therefor; of a slideable and tilttable bolt carried by the valise, a housing inclosing the bolt and having an opening, an actuating member for the bolt passing through the opening in the 25 housing and having on the outside thereof an abutment engageable with the housing wall to prevent tilting of the bolt, and movable in line with the opening when the bolt is slid to permit the bolt to be tilted, a latch keeper tongue on the handle, means on the bolt and engageable with said tongue for locking the handle to the valise, said means being operable by a sliding movement of the bolt, means in the valise and engageable 30 by the bolt for locking the valise, said means being operable by sliding and tilting movements of the bolt in the order named, and means for preventing such sliding movement of the bolt, said means being controlled by the aforesaid tongue.

35 bolt, means in the valise and engageable by the bolt for locking the valise, said means being operable by sliding and tilting movements of the bolt in the order named, and means for preventing such sliding movement of the bolt.

6. The combination with a valise or the 40 like, and a removable handle therefor; of a slideable and tilttable bolt carried by the valise, a housing inclosing the bolt and having an opening, an actuating member for the bolt passing through the opening in the 45 housing and having on the outside thereof an abutment engageable with the housing wall to prevent tilting of the bolt, and movable in line with the opening when the bolt is slid to permit the bolt to be tilted, a latch keeper tongue on the handle, means on the bolt and engageable with said tongue for locking the handle to the valise, said means being operable by a sliding movement of the bolt, means in the valise and engageable 50 by the bolt for locking the valise, said means being operable by sliding and tilting movements of the bolt in the order named, and means for preventing such sliding movement of the bolt, said means being controlled by 55 the aforesaid tongue.

In testimony whereof I affix my signature.

JOHN HEGERHORST.
